UNITED STATES PATENT OFFICE.

FRANCIS C. OSBORN, OF DETROIT, MICHIGAN.

PAPER-TUBE MACHINE.

945,862.

Specification of Letters Patent. Patented Jan. 11, 1910.

Application filed March 26, 1904, Serial No. 200,085. Renewed March 12, 1908. Serial No. 420,694.

To all whom it may concern:

Be it known that I, FRANCIS C. OSBORN, a citizen of the United States, residing at Detroit, in the county of Wayne and State 5 of Michigan, have invented a new and useful Improved Paper-Tube Machine, of which the following is a specification.

My invention relates to that type of machines by which continuous strips or bands 10 of paper or other similar material are carried spirally around a mandrel, cemented together, formed into continuous tubes and finally cut off into predetermined lengths.

The objects of my improvements are to 15 provide a machine of this class that can be quickly and easily adjusted for paper of varying widths and for tubes of different diameter; to provide means whereby the tubes are made of two or more layers, the 20 inner surface of the inner layer being evenly coated with paraffin and the inner surface of the outer layer being coated with glue or other cement; to provide means whereby the paraffin and glue will be evenly spread on 25 the strips of material; to provide guides for the paper that are easily adjustable; to provide means to accurately and cleanly cut the tube into lengths and to provide means to quickly dry the cement between the layers 30 of the material. I attain these objects by the construction illustrated in the accompanying drawings, in which—

Figure 1 is a general plan view of the machine. Fig. 2 is a plan and Figs. 3 to 7 35 and 17 to 20 inclusive are details of the saw driving and guiding means on a somewhat larger scale. Figs. 8, 9, and 16 are details of the driving pulleys of the tube forming belts. Figs. 10, 11, and 12 are details of the 40 paper guides. Figs. 13, 14 and 22 are details of the means for coating the material with cement or paraffin. Fig. 15 is a bottom view of the tube forming mandrel showing the auxiliary paper guide. Fig. 21 is a detail 45 of an auxiliary paper guide.

Similar reference characters refer to like parts throughout the several views of the drawings.

The base or bed A of the machine is similar to a lathe bed and is supported by legs 50 as shown in Fig. 1. On this bed are pivoted the swinging bed pieces B, and the arm B'. The pivots of the bed pieces B and arm B' are in line with each other. To one end 55 of each of the flat bed pieces B is secured a sliding support F for the pulley P', the dis-

tance between this pulley and the pulley P being varied by the screw F'. At the other end of the bed piece is the journal bracket J of the shaft C which bracket is pivoted on 60 the screw j. Outside of the bracket J is the upright bearing K of the stud shaft k of the pulley P. On the lower end of shaft k is the gear L which meshes with the pinion N on the shaft C. Inside of the bracket J 65 is the bearing O of the shaft R which shaft extends across and is splined in a sleeve r, carrying a pinion N' which meshes with a second gear L on a second shaft k which carries the pulley P' at its upper end. 70

At the head end of the base A is a small bracket a to which is pivoted an arm B' which is in turn pivoted to the bearing C' on the shaft C. This bearing is held from longitudinal movement on the shaft by the collars c. A link D is pivoted to all the swinging bed pieces by the screws j, and as the distance between the screws j is the same as between the pins X of the swinging bed pieces, the several bed pieces will always remain parallel to each other. The angle between the bed pieces and the base is determined by the graduated screw W supported by the bracket E secured to the base, which screw engages in the nut U which is pivoted 80 on the shaft C. The angle between the bed pieces and the base is determined by the graduated screw W supported by the bracket E secured to the base, which screw engages in the nut U which is pivoted 85 on the shaft C. The angle between the bed pieces and the base is determined by the graduated screw W supported by the bracket E secured to the base, which screw engages in the nut U which is pivoted 90 on the shaft C. As will be seen in Fig. 1, the screw W is graduated so the angle between the bed pieces B and the mandrel can be accurately determined.

The machine is driven from an over-head countershaft of any desired construction on which countershaft is secured a wide driving pulley which pulley is connected by 95 means of a driving belt with the pulley p.

The belts b pass around the mandrel M as shown in Figs. 1 and 15 and should be about as wide as the material wound. The hollow mandrel is securely fixed in the head H of 100 the machine. For the purpose of heating the mandrel so that the paraffin will penetrate the material of the strip and flow into the joint between the spirals and also to dry the cement, I provide a steam pipe bent upon itself extending the length of the mandrel and having ends m projecting from one end of the mandrel, which pipe ends may be connected to any steam source. 105

The means for coating the paper strip 110 with paraffin or glue is designated by G, and consists of the tank 70 supported on suitable

legs, and having secured to it the arms 71, carrying the pin 72 upon which is mounted the roll of paper 73. Journalized on the pin 74 is the roller 75 which dips into the liquid 5 paraffin or cement and carries it up against the lower face of the paper strip. This strip is guided between pins in the holes 76 in the arm 77 pivoted to the sides of the arms 71. The guide roll 78 is supported on the pin 80 10 secured in the frame 82 at the upper end of the rod 83. On the pin 81 are secured the collars 84 having fingers 85 which press against the coated side of the paper strip. Usually the coating material collects on the 15 outer edges of the strip but by means of the fingers 85 it is spread evenly toward the center.

It will be noticed that by reason of the roll 78 the coated strip will pass to the tube making machine with the coated side up, thus 20 not only avoiding any tendency of the coating to form drops as it does when the strip is fed to the machine with the coated side down, but also permitting the coating to 25 level itself on the flat surface.

To the base are secured the paper guides as shown in Fig. 1, each consisting of a base 30 90 to which is secured the arm 91 carrying the fixed part 92 of the guide and the slideable part 93, secured to the part 92 by bolts.

An auxiliary guide for the paper strips is shown in Fig. 15 and consists of the spirally arranged guide 95 secured to the mandrel M against which the inner strip of paper, 97, 35 will run, and over this guide 95, to position the strip 96, is secured an arm 98 which bears the guide 99 against which the outer strip 96 will run. With certain grades of paper, the guide shown in Fig. 21 is found 40 to be of great value. Instead of the short piece 95 as in Fig. 15, the part 100 is made to pass around the mandrel. The paper is wound upon the spiral sheet of brass 101, which extends until just before the place 45 where the first belt b embraces the mandrel. The mandrel M being of less diameter at this point, the tube will slip around it more easily. The arm 98 and guide 99 are used as before. The part 101 serves a similar purpose 50 to part 100 in that it acts as a shoulder to force the paper along the mandrel and acts on the inner strip after it has left the part 100 and after the outer strip has been wound upon it.

The operation of this portion of the 55 machine is as follows;—The paper strip 97 is carried around through its coating apparatus, through its guide 90 and is wound one turn spirally around the mandrel M. The 60 second strip 96 is then brought through to the mandrel and wound around the first strip. The short tube thus formed is then twisted around the mandrel by hand until about half a dozen turns have been formed. 65 The edge of the strip 97 is guided by the

guide 95 on the mandrel. After sufficient tubing has been formed in this manner by hand, the first belt b is put onto the pulleys P and P', and the machinery set in motion, which will cause the belt to continue the 70 work begun by hand, that of pulling the tube around the mandrel. As the tube grows, it will reach the second belt b, where the twisting tension will be repeated, preventing any tendency to untwist. The 75 steam heated mandrel will dry the glue before the tube passes off the end of the mandrel so that there is no danger of the tube opening up.

The mechanism for cutting the tube into 80 lengths and its operation will be explained later on.

Secured to the end of the base is an arm h which carries the means for cutting the tube into predetermined lengths. The outer end 85 of arm h is broadened to form a plate S to which is adjustably secured the table T. The table is slideable on the plate and adjusted sidewise by the small set screws t shown in Fig. 2. Attached to the table T 90 are two arms 1, between which is pivoted the frame 2, secured to the shaft 35, which projects toward the rear end of the machine. (Figs. 2 and 18.) This frame is braced by the cross pieces 50 and the vertical piece 51. 95 In the upper part of this frame is journalized the arbor 10 for the saw for cutting off the tubes. This arbor is slideable longitudinally in its journals and the position of the saw while cutting is controlled by the following 100 means: The tube as it comes from the mandrel abuts against the plate 14 on the end of the slideable rod 13 as shown in the dotted lines in Fig. 2. This rod is supported by and is slideable in the upper end of the arm 105 15 which is carried by the revoluble rod 35 and by the arm 8 carried on the saw arbor. Adjustable collars 52 on the rod 13 position the plate 14 with reference to the saw. The saw arbor is driven by a belt from an overhead pulley to the flanged pulley 12 on the sleeve 53, journalized in the bearing 54 of the frame 2 (Fig. 20). A feather 102 in the arbor keyseat forms the driving connection 110 between the arbor and the pulley. 115

To the frame 2 are attached two arms 4 and 5 which engage cams 55 and 56 respectively on the shaft 20 (Fig. 4). When therefore the shaft 20 is revolved the frame with the saw will be swung toward and away 120 from the tube. In the outer ends of the arms 1 is journalized the constantly running screw 3 which is intended to return the saw to its initial position, which screw is constantly driven by means of the pinion 36 125 which meshes with the gear 37 (Fig. 3) secured to the pulley 57, loosely mounted on the end of the shaft 20. This pulley is driven by a belt 58 on pulley 59 on the shaft C as shown in Fig. 1. The belt is tightened 130

by the pulley 60, on the arm 61, loosely mounted on the end of shaft 20. Secured to the shaft 20 is a disk 38 and loose on the outer end of the shaft is a second disk 39 having a pin 40 which passes through a slot near the end of the shaft. A screw 41 in the end of the shaft contacting with this pin regulates the pressure between the disks and the pulley and the frictional stress on the shaft. Secured to the shaft 20 are two collars 27 and 27^a, each having a pin 62—62^a projecting therefrom, the pins being at an angle to each other on the shaft and so positioned with reference to the cams, that the dogs 23 and 24 will alternately stop the shaft 20 when the frame 2 and with it the saw is in the withdrawn and in the operative positions respectively.

The arm 8 is pivoted on the saw arbor 20 and positioned by two small collars. To prevent it from revolving with the arbor it slides on a rod 9 secured to the swinging frame 2. To this arm is attached a short bar 29 (Fig. 3.) having a finger 28 which when the arbor, and with it the arm 8 has reached its outward position, contacts with the dog 24, moving it away from the pin 62^a and releases the shaft 20, which in turning swings the frame and saw back from the tube by the action of the cams. The dogs 23 and 24 return to position under the influence of the springs 5 shown in Fig. 3. On the arm 8 is a slidable plate 30 having a tooth 34 that engages the threads of the screw 3. This plate also has an upturned lug 33 and has its end bent to form the hook 31. The plate is held in its upper or lower position by the spring 64 acting on the lug 65. In the end of the arm 8 is a pin 26 that is spring pressed outward and is intended to engage the dog 23 and trip the same as the saw begins to move with the tube.

The operation of the sawing mechanism is as follows:—When the saw is in the position shown in Fig. 1, the arbor is free to slide under the pressure of the tube against the plate 14. The pin 26 in the arm 8 is to the left of the dog 23 (see Fig. 3) and the tooth 34 is free from the screw. Upon the tube pressing against the plate 14, the rod 13, the saw, the arbor and arm 8 are moved outward, the pin 26 moves dog 23 with it and pin 62 is released, permitting shaft 20 to turn part of a revolution which through the action of the cams on the arms 4 and 5 swings the frame 2 and with it the arbor and saw, toward the tube sufficiently far for the saw to cut through the wall of the tube. In so doing the hook 31 is brought in contact with the threads of the screw 3 causing the plate 30 to be pulled out, the spring 64 acting on lug 65 after passing the center to free the hook from the threads. The saw, arbor, arm 8, bar

29 and finger 28 move with the tube cutting through the wall of the tube as it turns under the pull of the belts 6 until the finger 28 contacts with dog 24, moving it to the right, (Fig. 3.) which releases the pin 62^a 70 and permits the shaft 20 to turn the remainder of the revolution or until the other pin 62 engages dog 23. In this part revolution, the cams swing the frame 2 back from the tube, bringing the tooth 34 into engagement with the screw 3, thus causing the arm 8, the arbor and the saw to be carried to the position shown in Fig. 3. When the pin 26 has passed the dog 23, which it can do owing to the beveled end, the pin 32 on 80 the screw shaft will contact with the lug 33 and force the tooth 34 out of engagement with the screw. The saw will then remain in its withdrawn position until sufficient length of tube is formed to again push plate 85 14 and the rod 13 outward. The amount of travel to the right and left is regulated by the position of fingers 28 on the bar 29.

To prevent the tube being pulled back by the saw when the frame 2 is withdrawn, 90 I secure the arm 16 to the rigid rod 19 carried by the table T. To this arm is secured the bar 17 with finger 18 which projects against the tube and prevents it moving to the left with the saw. (Fig. 7.) To 95 stiffen the saw arbor, I secure a bar 66 to the arm 8 and provide a bearing 67. This construction is omitted in Fig. 2 for the sake of clearness.

Having now explained my improvement, 100 what I claim as my invention and desire to secure by Letters Patent, is—

1. In a tube forming machine, the combination of a mandrel, a continuous belt passing around said mandrel, a pair of pulleys, one on either side of the mandrel for driving the belt, a swinging plate for supporting the pulleys, a second swinging plate, a link connecting the plates to keep them parallel to each other, a main driving shaft 110 mounted on the ends of said plates, and connections between the shaft and the pulleys.

2. In a tube forming machine, the combination of a base, a fixed mandrel carried by the base, a continuous winding belt passing 115 around said mandrel, a pair of pulleys, one on either side of the mandrel for driving the belt, a plate for supporting the pulleys pivoted to the base, a nut pivoted to one end of the plate, a screw carried by said base and engaging said nut to control the angle between the plate and base, a second plate pivoted to said base, a link connecting the plates to keep them parallel, a main driving shaft carried at the ends of said plates, and 120 connections between the shaft and pulleys.

3. In a tube forming machine, the combination of a base, a mandrel fixed to said base, a swinging plate pivotally mounted on said base, a second plate similarly mounted, 130

a link pivoted to said base, a bearing at the end of said link, bearings pivoted on the ends of said plates, a shaft journaled in said bearings, the centers of motion of said plates and link being in the same plane.

4. In a tube forming machine, the combination of a base, a mandrel carried by the base, a spiral guide passing around the mandrel to control the position of the first thickness of paper wound upon the mandrel, a second guide secured to the mandrel to control the position of the second thickness of paper wound upon the mandrel, and a flat band of metal spirally secured to the mandrel to increase its diameter and to serve to force the paper along the mandrel and act after the outer band of paper has been wound upon the first band.

5. In a tube forming machine, the combination of a base, a mandrel, means for winding paper strips upon said mandrel, and a paper guide carried by said base and comprising a frame and parallel jaws adjustable for different widths of material.

25 6. In a tube forming machine, the combination of a base, a swinging plate pivoted on said base, a mandrel secured to said base, a bearing pivoted on said plate, a shaft journaled in said bearing, a pulley on one end of said shaft to receive the belt to drive the machine, a pulley on the other end of the shaft, a tube cutting mechanism mounted on the end of the base, and a belt on said second pulley to operate said cutting mechanism.

35 7. In a tube forming machine, the combination of a mandrel fixedly mounted, a continuous winding belt passing around the mandrel, a pair of pulleys mounted on vertical stud shafts, one on either side of the mandrel for driving the belt, a swinging bed piece carrying the pulleys, a screw for swinging the bed piece whereby the angle between the mandrel and belt may be varied, a shaft mounted upon the swinging bed piece, a main driving pulley on the end of the shaft, gears connecting the main shaft and the stud shafts of the pulleys, and a slide adjustment for one of the stud shafts whereby the tension of the belt may be varied.

45 8. In a tube forming machine, the combination of a base, a swinging plate pivoted on said base, a mandrel secured to said base, a bearing pivoted on said plate, a shaft journaled in said bearing, and a pulley on one end of said shaft to receive the belt to drive the machine.

9. In a tube forming machine, the combination of a base, a mandrel mounted thereon, a plurality of swinging plates pivoted on said base, pulleys mounted on said plates, belts passing around said pulleys and said mandrel, an arm E mounted on said base, a graduated screw revolvably mounted in the end of said arm and adapted to control the

angle between the belt and the mandrel, and a link connecting said plates to keep them parallel to each other.

10. In a tube forming machine, the combination of a base, a swinging plate mounted on said base, a mandrel mounted on said base, pulleys mounted on said plate on opposite sides of the mandrel, a belt passing around said pulleys and mandrel, a bearing mounted on said plate, a shaft journaled in said bearing, and means mounted to move laterally independently of the base for driving said shaft.

11. In a tube forming machine, the combination of a base, a plurality of swinging plates mounted thereon, pulleys mounted on each of said plates, belts passing around the pulleys, bearings mounted on said plates, a shaft journaled in said bearings so as to be supported by the plates, and driving means for said shaft adapted to move in a horizontal plane with said bearings and shaft.

12. In a tube forming machine, the combination of a base, a plurality of swinging plates mounted thereon, a mandrel mounted on said base, pulleys mounted on said plates on opposite sides of the mandrel, belts passing around the pulleys and the mandrel, bearings carried by said plates and pivotally mounted thereon, a shaft journaled in the bearings, and driving means for the shaft mounted to move laterally with the shaft independently of the base.

13. In a tube forming machine, the combination of a base, a swinging plate mounted on the same, a mandrel extending over said plate, a mandrel support secured to one end of the base, an arm having one end pivotally connected to said base on the opposite side of the mandrel support from the swinging plate, bearings pivotally mounted on the said plate and arm, and a main driving shaft mounted in said bearings.

14. In a tube machine, the combination of a base, a swinging plate mounted thereon, a swinging arm mounted on said base, bearings pivotally mounted on said plate and arm, a driving shaft mounted in said bearings, and a screw connecting the said base and plate for adjusting the plate with reference to the base.

15. In a tube forming machine, the combination of a base, a mandrel carried thereby, means to wind two thicknesses of paper thereon, a spiral guide passing around the mandrel to control the position of the first thickness of paper wound upon the mandrel, and a flat band of metal spirally secured to the mandrel to increase its diameter and to serve to force the paper along the mandrel and act after the second band of paper has been wound upon the first band.

16. In a tube forming machine, the combination of a base, a swinging plate mounted on the same, a swinging arm mounted on

said base, bearings mounted on said plate and on the free end of said arm, a main driving shaft journaled in said bearings, and driving means for said shaft adapted to 5 move in a horizontal plane in the same arcs with the said bearings and shaft.

In testimony of which I have signed my

name to this specification in the presence of two subscribing witnesses.

FRANCIS C. OSBORN.
